2 Sheets-Sheet 2

UNITED STATES PATENT OFFICE.

JOSEPH SACHS, OF WEST HARTFORD, CONNECTICUT.

INCLOSED FUSED SWITCH.

Application filed August 7, 1923. Serial No. 656,182.

This invention is an improved inclosed switch ordinarily a fused switch, suitable for use as a service entrance switch as well as in other relations where it is desired to allow the customer or user to have access to the fuse or fuses without submitting him to the risk of accidental contact with live parts, or, if desired, without giving him an opportunity to take unmetered current. The general object is to attain this principal result in a practical way, as well as other results hereinafter disclosed, in a switch-box of smaller size and weight and lower cost of manufacture than has hitherto been considered possible within the limitations imposed by standard requirements for inclosed switches of this class.

In my copending application for inclosed fused switch, Serial No. 528,934 filed Jan. 13, 1922, I have disclosed an inclosed fused switch having an openable cover normally preventing access to the switch proper and having an additional cover means normally preventing access to the fuse and operable independently of the switch cover, the said means having a portion which is movable laterally so as to obstruct the switch closing movement of the switch handle whenever the fuse cover means is in position to permit access to the fuses; and as disclosed in the said application, the handle is so constructed as to engage a part of the fuse cover means other than the said laterally projectible portion thereof for preventing the movement of the said means to access permitting position when the handle is in switch closing position. A more specific object of the present invention is to provide a construction of the type described wherein the parts are so arranged that the laterally movable portion of the fuse cover means is directly obstructed by the part of the handle at the side of the box for thereby preventing the movement of the fuse cover means to access permitting position.

A further object of the invention is to provide a device of the class described having a novel and improved relationship between the switch cover and the fuse cover means whereby the fuse cover means is necessarily moved to an open position whenever the switch cover is opened.

A still further object of the invention is to provide various novel details of construction for the switch cover means.

Other objects of the invention will be ap-

parent from the following specification and claims.

The drawings illustrate one form of the invention as applied to a switch for a four-wire circuit, but without intending to limit the invention to this form or to any particular kind of circuit.

In the drawings, Fig. 1 is a perspective view of the said inclosed fuse with the cover closed and the circuit closed;

Figure 2, a similar view with the circuit open and the fuse section of the cover open;

Figure 3, the same box with both cover sections open and with the inspection flap open;

Figure 4, a perspective of the switch-block carrying the fuses and switching elements removed from the box;

Figure 5, an elevation of the box in its closed position;

Figure 6, a cross section of Figure 5 on line VI—VI; and

Figure 7, a cross section on line VII—VII of Figure 6.

The inclosed switch shown in these figures comprises a box, the body of which is of folded sheet metal, with a back 1 and side walls 2 and 2^a, and provided with knock-out or equivalent openings for the connection of wire conduits or other switch-box appurtenances, as usual. This body is intended to be secured in a vertical position on a building wall, so that the external operating handle presently referred to is located on one side of it, being shown on the right hand side. Such expressions as "vertical", "horizontal", "lateral" and the like will be used with the understanding that the device is normally secured in a vertical position as described but it will nevertheless be understood that I do not thereby limit myself to the location of the device in any one position.

The switch mechanism within the box comprises one or more movable switching elements and the appropriate contact clips and binding screws therefor and one or more corresponding fuses, all of which are so arranged that the fuses are in one part of the box and the switch parts and particularly the live or service side contacts and connections are in another, thereby permitting the closure means of the box to be organized so that the exposure of the fuses will not afford access to switch parts which are on the service side and hence alive even when the switch is open.

This arrangement is produced with a special economy of space and material by locat-

ing the main support for the fuses and switch mechanism in a position in the box removed from the back wall, and mounting the parts on opposite or different faces of said support.

5 In the present case, the said support is a base block 3, preferably, but not necessarily, made of one piece of insulating material, and mounted on two or more brackets 4 formed on or secured to opposite side walls of the box

10 body and near the open side or rim thereof and preferably about midway between the two end or top and bottom walls. The switching elements or connector blades 5 are hinged to the contact clips 6 secured to the inner side

15 of the base 3 and are adapted to close the circuit by engaging the rupture contact clips 7 secured to the same side of the base. These clips are intended to be connected by appropriate binding screws or wire-clamping

20 means 8 to the incoming service wires and these clips and wire connections are therefore live parts when the switch is open. The switching element and its appurtenant parts may be of any appropriate design and have

25 any desired mode of operation. The screws which hold the hinge clips 6 to the inner face of the base extend through the latter and carry the current to the corresponding fuse-receiving terminals 9 which are mounted on

30 the outer side of the base. The complementary fuse terminals 10 are secured to the same side of the base and associated with appropriate wire-connecting means or binding screws 11 for connection to the outgoing or

35 load wires. The incoming and outgoing wire connecting means are thus situated at opposite ends of the base. When the switching elements 5 are closed, the circuit is through the live contacts 7, the switching elements, the

40 clips 6, fuse clips 9, fuses and fuse clips 10 to the wire connections 11. When the circuit is opened the fuse terminals and the wire connections 11 are dead. Cartridge fuses F are illustrated but it will be understood that

45 they may be substituted by screw plug or other fuses, if desired by the obvious modification of the clips. One fuse is assigned to each switching element, and directly in front of it, and the base is provided with insulating barriers between the fuses and switch blades as more plainly shown in Fig. 4.

The switching elements 5 are conjointly operated by connection, by their insulating hooks 12, with the interior crank 13 of the

55 switch-operating means. In the present case this means comprises a round rod journaled in holes in the opposite side walls of the box and bent to form the crank 13 within the box and bent again outside the box to form a

60 crank arm 14 with a laterally extended handle 15. It is organized in the box so as to have little or no axial movement or end play and it is so related with reference to the switch elements or blades 5 that when it has

65 been rotated to close the circuit, the outside

crank arm 14 is then in the position indicated in Figs. 1 and 6, extending forwardly or transverse to the plane of the back wall of the box. It will be observed that the crank arm and handle of the operating means are located entirely at the side of the box adjacent the wall 2 thereof.

The box is provided with an openable front cover which serves when closed to prevent access to the switch or switches while permitting access to the fuse contacts. When the switches are located at the rear of a base such as 3 which extends substantially entirely across the front of the box the switch cover may be arranged to extend over only the end portion of the box which is not occupied by the base 3. I have shown such a cover at 17. The character of the opening movement of the cover 17 can be varied but I prefer to mount the cover for pivotal movement. As illustrated it is pivotally mounted by means of a hinge 18 for movement about a vertical axis.

In addition to the openable cover for the switches I provide a front cover means which normally serves to prevent access to the fuse contacts and which is movable independently of the aforesaid switch cover to permit such access. In accordance with one phase of the invention the said cover means includes a laterally movable portion which, when the cover means is in the position for permitting access to the fuses, is located in a projecting position at one side of the box and in the path of the movement of the handle part 14. In obtaining access to the fuse contacts the normal procedure is to first move the switch handle to open the switches and to then move the cover means for the fuses to expose the fuses. As already stated, whenever the said cover means is in access permitting position the said laterally movable portion thereof is located in the path of movement of the handle and therefore serves to prevent movement of the handle to switch closing position. Furthermore the arrangement is such that the handle when in switch closing position or, in fact, when in any position other than the position corresponding to the fully open position of the switches, directly obstructs the movement of the said laterally movable portion of the fuse cover means so as to thereby prevent movement of the said means to access permitting position.

The details of construction of the fuse cover means may be widely varied but I have illustrated a fuse cover means which comprises a sidewise opening cover. When a sidewise opening cover is provided the said cover has a portion which partakes directly of the sidewise movement so as to project or be located in the path of movement of the said side part of the handle for the purposes already set forth. Different types of sidewise movement may be provided but I have

illustrated a cover constructed and arranged for a sidewise pivotal movement.

The fuse cover 16 is shown as being hinged to the box body on that side which is adjacent the path of the side handle crank 14 and correlated therewith so that the crank arm 14 obstructs opening of the cover when in its forward or circuit-closing position, just referred to. In this way, the cover cannot be opened to expose the fuses until the circuit is open and no current is passing through them. This desirable relationship is established by providing the fuse cover 16 with a relatively deep side flange by which it is hinged to the body at 18^a, 18^b, and preferably by making it chambered, that is to say, with an interior space which may be occupied, when the cover is closed, by such parts of the fuse or fuse-holding means as project beyond the limits of the box body proper. The crank arm 14 which is located wholly at one side of the box, without any part which overhangs the cover, will satisfactorily cooperate with such a cover because of the depth of the hinged flange or side wall thereof and because of the considerable lateral movement of such side wall incident to the swinging of the cover on its hinge axis. It will be observed that the flange 19 constitutes the laterally movable portion of the cover means as hereinbefore referred to. This interlocking organization of cover and side handle is very simple and effective and easily made and constitutes an important part of the present invention. When the switch cover 17 and the fuse cover 16 are both pivoted for lateral movement their pivoted axes may be coincident and they are so shown. The fuse cover 16 may be additionally held in closed position by means of a latch 24.

It will be observed that the laterally movable portion of the fuse cover means, in this case the flange 19, terminates at a horizontal edge adjacent the switch opening position of the handle 14 as clearly shown in Fig. 2. As illustrated the switch opening position of the handle is the lowermost position thereof and the said cover portion terminates with its horizontal bottom edge 19^a immediately above the said position of the handle.

It is ordinarily preferable to so connect or relate the switch cover and the fuse cover means that the said fuse cover means is moved to an open position whenever the switch cover is opened thus ensuring the complete opening of the box for convenient inspection of the entire interior thereof by a single opening movement. The necessary connecting and co-relating of the switch cover and the fuse cover means may be variously effected but when there are provided a switch cover and a fuse cover both hinged for sidewise pivotal movement about a common axis it is convenient to so construct the covers that the fuse

cover overlaps the switch cover with the result that it is necessarily opened when the switch cover is opened. As illustrated the switch cover 17 is provided with a forward projecting flange 21 which is overlapped by a flange 16^a on the fuse cover 16. Obviously when the switch cover 17 is moved to open position as shown in Fig. 3 the fuse cover 16 is also moved to an open position.

It may be desirable to so construct and arrange the parts that the handle, when in switch closing position, serves not only to prevent opening of the fuse cover but also serves to prevent opening of the switch cover. In the present case this result is obtained by so the overlapping relationship of the fuse cover and switch cover as already described. Obviously when the fuse cover is held in closed position as shown in Fig. 1 the switch cover is also held in closed position. 85

In order to further facilitate access to the switches I may provide a cover section or inspection door additional to the cover 17 already described. This door is shown at 22 being hinged to the bottom end wall of the box. The cover section 22 is in effect, merely a part of the corresponding end wall of the box, hinged to form a flap or door and provided with end flanges 23 and otherwise shaped so that when it is closed it can be embraced and held closed by the flange of the main switch cover section 17. The two cover sections 17 and 22 together protect or close that part of the box through which access can be had to the live or service side switch parts, the section 17 being appropriately proportioned so that it extends close enough to the switch base to prevent accidental contact by the user with the live parts when the fuse-cover is open, and if need be, so close to the base as to prevent the insertion of wires into contact with such parts. The section 17 is provided with a latch or sealing means 20 so that it and the flap door 22 can be sealed against opening by unauthorized persons, but the section 17 can be closed when the flap door is open. The flap door section 22 serves the two purposes of enlarging the access to the switch parts which is provided by the section 17, and it also affords an inspection opening through which the interior switch mechanism can be observed, when in operation. For this purpose it is necessary, in the form shown, that the main and auxiliary cover sections shall be both closed in order to permit the use of the crank and handle. For example, if the inspection flap or door 22 is opened, as in Fig. 3, and the cover sections 16 and 17 are then closed, the switch elements can be moved back and forth by the handle and can at the same time be watched and examined through the inspection opening. The position of the flap door at one end of the box and hence nearer to the back wall of the box body than any of the other sections, makes it possible to see 130

under or back of the switch base, where the switch blades are mounted. I have illustrated only one inspection flap but obviously it can be duplicated at the opposite end, or 5 even at the sides, if desired, so as to provide still greater accessibility to the space behind the base. It is ordinarily not necessary to protect the load side wire connections 11 from accidental contact, especially when the cover 10 and handle are interlocked as described, since these parts are dead when the cover is open but, in the event that the box is required to be thoroughly proof against theft it is sometimes desired to maintain a complete obstruction 15 to the space under the base 3 when the fuse cover only is open, and this result can be attained in the present case by duplicating the auxiliary cover section 17 at the opposite end of the box and sealing it in the same way 20 so that the opening of the chambered section will not expose the interior of the box on the load side.

While it is preferred to hinge the two auxiliary cover sections, 17 and 22, in the manner shown in the drawings, it is obvious 25 that they can be otherwise arranged so as to perform their principal function, which is to provide a liberal opening and direct access to the live terminals and the space under the 30 switch base, and preferably by locating such cover sections, or cover means, at right angles to each other and on two adjacent sides of the box so that they open a corner, rather than a side, of the box. This arrangement of the 35 cover, whether consisting of separate sections as in the present case or otherwise, will be recognized as affording special conveniences quite irrespective of the shape of the fuse cover and its relation to the switch operating handle, as well as of the use to which 40 the switch is designed, whether service or individual uses.

Claims:

1. A fused switch comprising in combination, an inclosing box, fuse contacts in the box, a switch in the box, an openable front cover serving when closed to prevent access to the switch while permitting access to the fuse contacts, additional front cover means 45 normally serving to prevent access to the fuse contacts and movable independently of the first said cover to permit such access, the said cover means including a laterally movable portion which, whenever the first said 50 cover is closed and the said cover means is in access permitting position, projects at one side of the box, and an exterior switch operating handle having at least a part thereof adjacent the wall of the box at the last said side thereof and movable 55 from switch opening position to switch closing position in a path which is directly obstructed by a horizontal edge of the said portion of the fuse cover means when projecting as aforesaid, the said side part of the handle when in any position other than that corresponding to the fully open position of the switch directly obstructing movement of the said laterally and parallelly movable portion of the fuse cover means so as to prevent movement of the said means to access permitting 60 position.

65 2. A fused switch comprising in combination, an inclosing box, fuse contacts in the box, a switch in the box, an openable front cover serving when closed to prevent access to the switch while permitting access to the fuse 65

70 directly obstructing movement of the said laterally movable portion of the fuse cover means so as to prevent movement of the said means to access permitting position.

75 3. A fused switch comprising in combination, an inclosing box, an insulating base in the box, fuse receiving contacts on one face of the base, a switch adjacent another face of the base, an openable front cover serving when closed to prevent access to the switch 75 while permitting access to the fuse contacts, additional front cover means normally serving to prevent access to the fuse contacts and movable independently of the first said cover to permit such access, the said cover means 80 including a laterally movable portion which, whenever the first said cover is closed and the said cover means is in access permitting position, projects at one side of the box, and an exterior switch operating handle having 85 at least a part thereof adjacent the wall of the box at the last said side thereof and movable from switch opening position to switch closing position in a path which is directly obstructed by the said portion of the fuse cover 90 means when projecting as aforesaid, the said side part of the handle when in switch closing position directly obstructing movement of the said laterally movable portion of the fuse cover means so as to prevent movement of the said means to access permitting position. 95

100 4. A fused switch comprising in combination, an inclosing box, fuse contacts in the box, a switch in the box, an openable front cover serving when closed to prevent access to the switch while permitting access to the fuse contacts, additional front cover means normally serving to prevent access to the fuse contacts and movable independently of the first said cover to permit such access, the said 105 cover means including a portion which is laterally movable in parallelism and which, whenever the first said cover is closed and the said cover means is in access permitting position, projects at one side of the box, and an exterior switch operating handle having 110 at least a part thereof adjacent the wall of the box at the last said side thereof and movable from switch opening position to switch closing position in a path which is directly obstructed by a horizontal edge of the said portion of the fuse cover means when projecting as aforesaid, the said side part of the handle when in any position other than that corresponding to the fully open position of the switch directly obstructing movement of the said laterally and parallelly movable portion of the fuse cover means so as to prevent movement of the said means to access permitting 115 position. 120

125 5. A fused switch comprising in combination, an inclosing box, fuse contacts in the box, a switch in the box, an openable front cover serving when closed to prevent access to the switch while permitting access to the fuse 130

- contacts, additional front cover means normally serving to prevent access to the fuse contacts, additional front cover means normally serving to prevent access to the fuse 5 contacts and movable independently of the first said cover to permit such access, the said cover means including a laterally movable portion which, whenever the first said cover is closed and the said cover means is in access 10 permitting position, projects at one side of the box, means serving to cause an opening movement of the said fuse cover means whenever the first said cover is opened, and an exterior switch operating handle having at least 15 a part thereof adjacent the wall of the box at the last said side thereof and movable from switch opening position to switch closing position in a path which is directly obstructed by the said portion of the fuse cover means 20 when projecting as aforesaid, the said side part of the handle when in switch closing position directly obstructing movement of the said laterally movable portion of the fuse cover means so as to prevent movement of the 25 said means to access permitting position.
5. A fused switch comprising in combination, an inclosing box, fuse contacts in the box, a switch in the box, an openable front cover serving when closed to prevent access 30 to the switch while permitting access to the fuse contacts, an additional front cover normally serving to prevent access to the fuse contacts and openable independently of the first said cover to permit such access, the said 35 cover having a portion which, whenever the first said cover is closed and the second said cover is open, projects at one side of the box, and an exterior switch operating handle having at least a part thereof adjacent the wall 40 of the box at the last said side thereof and movable from switch opening position to switch closing position in a path which is directly obstructed by the said portion of the fuse cover when projecting as aforesaid, the 45 said side part of the handle when in switch closing position directly obstructing movement of the said portion of the fuse cover to prevent movement of the said cover to access permitting position.
6. A fused switch comprising in combination, an inclosing box, fuse contacts in the box, a switch in the box, an openable front cover serving when closed to prevent access to the 50 switch while permitting access to the fuse contacts, an additional front cover normally serving to prevent access to the fuse contacts and openable independently of the first said cover to permit such access, the said cover having a portion which, whenever the first 55 said cover is closed and the second said cover is open, projects at one side of the box, and an exterior switch operating handle having at least a part thereof adjacent the wall of the 60 box at the last said side thereof and movable from switch opening position to switch closing position in a path which is directly obstructed by the said portion of the fuse cover when projecting as aforesaid, the said side part of the handle when in switch closing position directly obstructing movement of the said portion of the fuse cover to prevent movement of the said cover to access permitting position.
7. A fused switch comprising in combination, an inclosing box, fuse contacts in the 65 box, a switch in the box, an openable front cover serving when closed to prevent access to the switch while permitting access to the fuse contacts, an additional front cover normally serving to prevent access to the fuse contacts and openable independently of the first said cover to permit such access, the said cover having a portion which is directly obstructed by the said portion of the fuse cover to prevent movement of the said cover to access permitting position.
8. A fused switch comprising in combination, an inclosing box, fuse contacts in the box, a switch in the box, an openable front cover serving when closed to prevent access to the switch while permitting access to the fuse contacts, an additional front cover normally 70 serving to prevent access to the fuse contacts and openable independently of the first said cover to permit such access, the said cover having a portion which is moved in parallelism to a projecting position at one side of the box whenever the first said cover is closed and the second said cover is opened, and an exterior switch operating handle having at least a part thereof adjacent the wall of the box at the last said side thereof and movable from switch opening position to switch closing position in a path which is directly obstructed by a horizontal edge of the said portion of the fuse cover when in projecting position as aforesaid, the said side part of the handle when in any position other than that corresponding to the fully open position of the switch directly obstructing movement of the said laterally and parallelly movable portion of the fuse cover to prevent movement of the said cover to access permitting position.
9. An externally operated inclosed switch comprising a box body containing a switching element, a cover having a relatively deep flange or side wall hinged to a side wall of

- 5 said body, and an exterior crank arm and handle for operating said switching element journalled to swing at one side of the box adjacent and parallel to said deep flange when the cover is closed, the said crank arm and handle being adapted to be directly engaged by the flanged side of the cover to thereby obstruct cover opening when the circuit is closed.
- 10 10. An inclosed switch comprising a box body, a chambered cover having a side wall hinged to the body, fused switch mechanism mounted on the box with the fuse or fuses projecting into the cover when closed, and a switch-operating crank arm having a handle journalled to swing entirely at one side of the box adjacent and parallel to said hinged cover side wall, the said handle serving when the switch is closed to directly engage the side wall of the cover to obstruct opening of the said cover.
- 15 11. An inclosed switch comprising a box body, a cover having a relatively deep side wall hinged to the body, fused switch mechanism in the box including a fuse exposed by opening the cover, a switching element wholly contained within the body of the box and not exposed by opening the cover, and operating means for said element having
- 20 a side handle crank arm swinging adjacent and parallel to the deep hinged side wall of the cover to be engaged by the outer face of said wall to obstruct cover opening when the switching element is in its closed position.
- 25 12. An inclosed fused switch comprising a box body, a chambered cover having a side wall hinged to the body, a switch base supported in the body and near the rim thereof, a switching element mounted on the inner side of the base, a fuse mounted on the outer side thereof and projecting into the chamber of the cover, and an external switch-operating crank and handle located wholly at one side of the box body and swinging adjacent
- 30 and parallel to the hinged cover side wall to obstruct cover opening when the circuit is closed.
- 35 13. An inclosed switch comprising a box body containing a switching element and having a flanged cover hinged to its side wall, in combination with a switch-operating means comprising a rod bent to form an interior crank connected to said element and an exterior crank arm terminating in a handle portion located entirely at one side of the box and swinging adjacent and in a plane parallel to said wall and hinge axis and thereby obstructing opening of the cover when in its circuit closing position.
- 40 14. An externally-operated, inclosed switch comprising a box body, a chambered cover having one of its chamber-forming side walls hinged to the body, a switching element in the box, an operating means therefor journalled in the box and having an exterior
- 45 crank arm and handle swinging adjacent and parallel to said hinged cover side wall when the cover is closed, the last said side wall of the said cover being arranged to encounter the handle-carrying part of said crank arm when the latter occupies its switch closing position to obstruct cover opening and the said side wall serving when the cover is open to encounter the handle carrying part of the said crank arm to prevent movement thereof from switch opening to switch closing position.
- 50 15. An inclosed fused switch comprising a box body containing switch mechanism including a switching element and its apurtenant contacts and wire connecting means and a fuse, a cover section having a deep side wall hinged to the body and covering the fuse, a second cover section for preventing access to the live switch parts, means for sealing the said second section in closed position, and an operating means for said switching element comprising an external crank arm swinging adjacent and parallel to said hinged cover side wall entirely at one side thereof on the outer side of the hinge thereof and engaged thereby to obstruct cover opening and to prevent exposure of the fuse when the circuit is closed.
- 55 16. An inclosed fused switch comprising a box body containing switch mechanism including a switching element and its wire connecting means and a fuse, a primary cover section hinged by a relatively deep side wall to the body and covering the fuse, a second cover section for preventing access to the live switch parts, arranged to be retained in closed position by the closure of the fuse-covering section, and an external operating crank arm for said switching element swinging adjacent and parallel to the hinged side wall of said fuse-covering cover section and entirely at one side thereof to prevent opening of both sections when the switch is closed.
- 60 17. An inclosed fused switch comprising a box body, a primary cover hinged thereto, switch mechanism therein having a fuse accessible to the user by opening the cover and including a switching element and service-side wire connections which are unexposed and relatively inaccessible on opening said cover, in combination with an external operating means for said element mounted in the box body and adapted to prevent opening of said cover when in its circuit-closing position, a second cover member adapted to expose said switching element when the first said cover is open, means whereby the second said member must be closed when the first said cover is closed, and means independent of the first said cover for locking the second said cover in closed position.
- 65 18. An inclosed fused switch comprising a box body containing switch mechanism having a fuse, a cover adapted to expose the

- fuse but not the live or service-side parts of the switch mechanism, a second cover means disposed on both sides of a corner of the switch inclosure adapted to be opened to expose said live parts, and a sealing device for the said second cover means.
19. An inclosed fused switch comprising a box body containing switch mechanism having a fuse, a cover adapted to expose the fuse but not the live or service-side parts, a second cover means disposed at the corner of the switch inclosure, part thereof being on the front of the inclosure and part at the end thereof and adapted to be opened to expose said service-side parts, and means for locking the said second cover means.
20. An inclosed fused switch comprising a box body, a switch base therein having a fuse on its outer side and switch mechanism on its inner side, a cover for exposing the fuse, and another cover normally disposed at an angle to the fuse cover for providing inspection access to the inner side of the switch base.
21. An inclosed fused switch comprising a box body, a switch base therein having a fuse on its outer side and switch mechanism on its inner side, a front cover for exposing the fuse, a crank handle for operating the switch adapted to obstruct opening of said cover, a door in the end wall of the box body adapted to be open when the crank handle is in its circuit-closing position, and means for sealing said door independently of the fuse cover.
22. A fused switch comprising in combination, an inclosing box, fuse contacts in the box, a switch in the box, an openable front cover serving when closed to prevent access to the switch while permitting access to the fuse contacts, a front cover serving when closed to prevent access to the fuse contacts and openable independently of the first said cover to permit such access, an exterior switch operating handle having at least a part thereof adjacent one side wall of the box, and means associated with the said covers and the said side part of the handle for preventing opening of either cover when the handle is in switch closing position, the said means permitting opening of both covers independently of the handle when the handle is in switch opening position.
23. An inclosed fused switch comprising a box body, a switch base therein having a fuse on its outer side and switch mechanism on its inner side, a cover for exposing the fuse but not the live parts, a crank handle for obstructing opening of such cover when the circuit is closed, and an independent second cover adapted to expose said live parts, the said second cover being engaged and held closed by the fuse cover.
24. An inclosed fused switch comprising a box body, a primary cover section hinged thereto, switch mechanism therein including a fuse accessible to the user by opening said cover section, a switching element and service-side connection in said body unexposed on opening said cover section, and two other cover sections normally excluding access to said service connections, one of the last said sections being incapable of opening except by opening the primary section and the other being adapted to permit inspection of the box interior when said primary section is closed, in combination with an external operating handle for the switching element adapted to obstruct opening of the primary cover section while the circuit is closed.
25. An inclosed switch comprising a box body containing switch mechanism including a switching element and its service side wire connections and a fuse, a cover section adapted to expose the fuse, a second cover section preventing access to the service-side parts, a seal for said second section, an external operating crank arm for said switching element adapted to prevent opening of the fuse section when the circuit is closed, and a hinged inspection door adapted to be locked closed by said second cover section.
26. An inclosed fused switch comprising a box body, a switch base therein having a fuse on its outer side and switch mechanism on its inner side, a cover section adapted to expose the fuse but not the live parts of the switch mechanism, a second cover section adapted to bridge and close the space between said base and one end of the box body, both said cover sections being hinged to the box body, and means to prevent the opening of either cover section while the circuit is closed.
27. An inclosed fused switch comprising a box body, a switch base therein having a fuse on its outer side and switch mechanism and wire connections on its other sides, a chambered cover section adapted to expose the fuse, a relatively shallow second cover section adapted to expose the wire connections, both sections being hinged to the same wall of the box body, and means to prevent opening of the fuse cover section while the circuit is closed.

In testimony whereof, I have signed this specification.

JOSEPH SACHS.

CERTIFICATE OF CORRECTION.

Patent No. 1,721,494.

Granted July 16, 1929, to

JOSEPH SACHS.

It is hereby certified that error appears in the printed specification of the above numbered patent requiring correction as follows: Page 5, lines 1 to 3, claim 4, strike out the words and comma "additional front cover means normally serving to prevent access to the fuse contacts, "; and that the said Letters Patent should be read with this correction therein that the same may conform to the record of the case in the Patent Office.

Signed and sealed this 29th day of October, A. D. 1929.

(Seal)

M. J. Moore,
Acting Commissioner of Patents.
